WADDING FOR WHALE GUNS

Application filed April 28, 1932, Serial No. 608,080, and in Norway April 13, 1931.

This invention relates to a wadding for whale guns or the like consisting of a plurality of round plates placed upon each other and kept together as a unit with end pieces 5 of rubber or the like.

One object of the invention is to obtain the most suitable yielding power between projectile (harpoon) and charge of gunpowder in the firing moment. A further object is to provide the best possible tightening means although the wadding at the same time is of such a size that it can be easily introduced into the gun barrel.

The elastic properties of a gunwad are of 15 greatest importance in order to obtain the same shooting results from one shot to another. A harpoon, for instance, can easily be damaged (deformed), if the elasticity is insufficient and the shots will be irregular. A 20 good tightening entails that the powder gases do not tear asunder the wadding in the firing moment, but that always the same high discharge speed is obtained and as a result thereof a great range and even shooting 25 results.

The characteristic feature of this invention is that the plates alternately are of different diameter and that the larger plates consist of a soft and elastic material, such as felt, while 30 the smaller plates consist of a harder material.

The yielding power is obtained by means of the felt but may also be produced thereby 35 that adjacent plates are convex in the same or opposite directions and in the same or different degree. Although these plates rest against each other they are not pressed close together, but admit of a further pressing together during the firing, by means of which 40 the kick against the harpoon base is modified. This elasticity can be obtained merely by a sufficient softness of the plates. They can consist of relatively thin elastic plates 45 of metal or pasteboard to alternate with relatively thick plates of fulled felting.

If plates of harder and more soft material alternate, and moreover the diameter of the harder or stiffer, i. e. the less elastic plates 50 is made equal to or smaller than the calibre of the gun barrel, and the diameters of the

more soft plates larger than the calibre, the best result is obtained, because when pressed together during the firing the soft plates spread a little and press with their edges against the walls of the gun barrel, so that 55 a good packing for the powder gases is secured. When the wadding is not pressed together it is consequently thinner than during the firing and can therefore easily be inserted into the gun barrel. 60

The attached drawing shows by way of example different forms of the invention.

Figs. 1 and 2 show the complete wadding seen from the side and Figs. 3-6 some of its plates of different form and in crosssection. 65

Plates 2 and 3 are placed between thicker endplates 1 and 4, which are suitably made of India rubber. Plate 1 serves as support for the harpoon (the projectile), plate 4 as holder of a pasteboard cap 5 for the charge 70 of gunpowder by means of cords 6. Every other plate 2 is made of soft or supple material, e. g. felting, and the plates 3 of harder or stiffer material, such as pasteboard or metal. 75

The soft plates 2 have a larger diameter than the gun calibre, and the hard plates 3 preferably a little smaller diameter than the gun calibre. When the soft plates are made convex, as the plates 2a in Fig. 3, and the 80 intervening plates 3a are plane, an elasticity ensues at the pressing together axially, not only on account of the suppleness of the plates 2a but also as a result of their convex form. When pressed together the material 85 in the plates 2a is moved outwards against the walls of the gun bore. In Fig. 4 the plates 2b are made thicker in the middle. Also in this event the plates 2b become extended radially when pressed by the plates 90 3b, and a good packing against the walls of the gun bore is procured. The plates can have also other forms. The larger plates 2c can thus be arranged in pairs and be convex or conical with the bases against each other, 95 as shown in Fig. 5. And the plates 3c can be plane or convex. They can also be arranged in pairs such as the plates 3d in Fig. 6. At the pressing together axially the plates 3d press the material in the felt plates 100

$2d$ outwards against the walls of the gun bore.

The circumference of the larger plates can be cylindrical, as in Fig. 5, or conical, as shown in Fig. 3.

It is not necessary that every other plate is equal, the plates 2 and 3 can instead be grouped otherwise, if only the yielding power is obtained, as shown in Figs. 5 and 6.

10 The plates are held together in a suitable manner, for instance by a metal wire 8 pulled through, so that the wadding and the charge of gunpowder constitute a unit. One or several of the foremost plates 2, 3 next to the 15 plate 1, are soaked in tallow or other fatty substance in order to prevent water from coming in to the gunpowder.

10 The India rubber plate 4a in Fig. 2 can be provided with grooves 7 which form intervening flanges similar to the flanges formed by the plates 2 and 3 and lying against the wall of the gun bore and constitute a good packing for the gunpowder gases, in order to protect the felt plates against the powder 25 gases during the firing. The plate 4a can also be formed of several thin plates of mutually different diameter and degree of hardness.

I claim:—

30 1. A wadding for whale guns comprising a plurality of round plates upon each other and kept together as a unit, the plates being alternately of different diameter and the larger plates consisting of a soft and elastic 35 material while the smaller plates consist of harder material, the soft plates being plane and the hard plates being conical and arranged in pairs with the bases against each other.

40 2. A wadding for whale guns comprising a plurality of round plates upon each other and kept together as a unit, the plates being alternately of different diameter and the larger plates consisting of a soft and elastic 45 material while the smaller plates consist of harder material, the soft plates being plane and the hard plates being conical and arranged in pairs with the bases against each other, more than one pair of hard plates 50 arranged between the soft plates.

3. A wadding for whale guns comprising a plurality of round plates upon each other and kept together as a unit, the plates being alternately of different diameter, the larger 55 plates consisting of fulled felting and the smaller plates of pasteboard, the soft plates being plane and the hard plates being conical and arranged in pairs with the bases against each other.

60 4. A wadding for whale guns comprising a plurality of round plates upon each other and kept together as a unit, the plates being alternately of different diameter, the larger plates consisting of fulled felting and 65 the smaller plates of pasteboard, the soft

plates being plane and the hard plates being conical and arranged in pairs with the bases against each other, more than one pair of hard plates arranged between the soft plates.

70

5. A wadding for whale guns comprising a plurality of round plates upon each other and kept together as a unit, the plates being alternately of different diameter, the larger plates consisting of fulled felting and the smaller plates of pasteboard, the soft plates being plane and the hard plates being conical and arranged in pairs with the bases against each other, more than one pair of hard plates arranged between the soft plates, 75 all the plates being held together by means of a metal wire.

80

In testimony whereof I have signed my name to this specification.
